US00D684855S

(12) United States Design Patent
BeVier et al.

(10) Patent No.: US D684,855 S
(b4) Date of Patent: * Jun. 25, 2013

(54) TRAY

(75) Inventors: Corey Jacob BeVier, Sun Prairie, WI (US); Bonita M. Hinze, Sun Prairie, WI (US); MeeWha Lee, Waunakee, WI (US); Jo-Ann Clark, Boat of Garten (GB)

(73) Assignee: Kraft Foods Group Brands LLC, Northfield, IL (US)

() Term: 14 Years

(21) Appl. No.: 29/397,075

(22) Filed: Jul. 11, 2011

(51) LOC (9) Cl. 09-03

(52) U.S. Cl.

USPC D9/429; D9/432

(58) Field of Classification Search

USPC D9/414, 416, 418, 420–429, 430–433, D9/455–456; D3/272, 273, 302; 206/267, 206/269, 270, 273, 299, 737, 740, 822; 229/100, 229/101, 101.3, 106, 108–122; D7/566, 584–587

See application file for complete search history.
